UNITED STATES PATENT OFFICE.

ROBERT W. BURROWS, OF PETALUMA, CALIFORNIA.

EGG CUSHION.

Application filed May 10, 1926. Serial No. 107,879.

The present invention relates to egg carriers and more particularly to an improved cushioning flat and filler designed to separate the horizontal layers of eggs within a carrier and on the cushions of which are adapted to rest the positioned eggs, such cushioned flat and filler being designed and arranged to reduce breakage of the eggs to a minimum while in the carrier.

A further object of the invention is to provide an egg flat, the cushioning or upper surface of which is formed from a separate sheet, scored, cut and bent to afford cushioning members separated by grooves or channels in which are received the lower edges of the interlocked strips forming separating means, and dividing the layer into individual egg pockets.

A further object is to provide a scored, cut and folded sheet of a type which may be adhesively secured to the top surface of a supporting base or sheet, enabling the top sheet to be formed prior to its attachment to its supporting sheet, whereby the cost of manufacture will be comparatively low.

A further object is to provide a cushioned flat wherein an individual cushioning member is provided for each egg, certain opposing sides of the cushioning members being integral with the sheet from which the cushion is formed and affording an integral support therefor; certain other side members being integral with the cushion member and adapted to contact with and rest on the lower sheet, thereby affording a peripheral support for the cushioning member.

With the above mentioned and other objects in view, the invention consists in the novel construction and combination of parts hereinafter described, illustrated in the accompanying drawings and pointed out in the claim hereto appended; it being understood that various changes in the form, proportion, size and minor details of construction within the scope of the claim may be resorted to without departing from the spirit or sacrificing any of the advantages of the invention.

To comprehend the invention, reference is directed to the accompanying drawings, wherein—

Fig. 1 is a sectional side elevation of an egg carrier provided with the preferred embodiment of my invention.

Fig. 2 is a plan view of a part of the same.

Fig. 3 is an enlarged sectional perspective view of part of the preferred embodiment of my invention.

Figure 4 is a detailed plan view of one of the cushions in Figure 2.

In the drawings wherein like characters of reference designate corresponding parts—A indicates a crate or box, of the usual construction, B the cushioned flat and C the filler for positioning between adjacent flats for providing individual egg cells arranged in tiers and in rows disposed at right angles to each other. Each flat consists of a layer separating sheet 1 and a surface sheet 2 secured to the upper surface thereof. Said surface sheet 2 prior to being positioned to overlie the sheet 1, is provided with parallel spaced groups of parallel score lines 3 and 4, and is further provided with parallel cuts 5 disposed at right angles to the groups of score lines 3 and 4 to provide between them a rectangular portion 6, hereinafter referred to as a platform.

Each cut 5 is flanged on each side by a score line 7 of a length corresponding to the distance between the score lines 4 at opposite sides of any given platform 6.

The material at the ends of the score lines 7 is cut away forming a notch 8. After being cut and scored the surface sheet is bent on the score lines 3 and 4 in such manner as to cause the platforms 6 to be disposed all in the same plane and offset above that portion of the sheet lying between the scores 3 of the respective groups.

The portions 9, one located at each opposite edge of the platform, disposed at right angles to the portions provided by bending score lines 3 and 4 constitute flaps which are bent downwardly, as in the drawings.

The surface sheet cut and bent as above described, is positioned to overlie the main sheet 1, and the portions of said surface sheet 2 lying between score lines 3 of the respective groups, adhesively or otherwise secured to the upper surface of the sheet 1, provides a plurality of cushion supports arranged in parallel rows disposed at right angles to each other, the respective platforms 6 of which are peripherally supported by the portions 9 and 10. The respective portions of the surface sheet lying parallel with the cuts 5 and lying between the scores 110

3 afford seats or grooves in which rest the lower edges of the respective interlocked strips 11, which provide the individual cells for the eggs, the base of each of which is 5 formed by one of said platforms 6.

If desired, each platform may be formed centrally with an aperture 12 for receiving the butt or point of the egg and which aperture may be of any suitable size; if small, I 10 prefer to cut a portion of the platform on lines 13 radiating from the aperture 12.

From the foregoing, it will be seen that a cushion is provided for each cell; that the respective flats are readily adapted for re- 15 use, and due to their two-part construction and the formation of the surface sheet prior to its attachment with its supporting sheet, the surface sheet is capable of being cheaply constructed and attached to the supporting 20 sheet at very little cost.

I claim:—

An egg carrier consisting in part of an

egg layer separating flat, a surface sheet secured thereto, said surface sheet provided with parallel spaced groups of parallel score 25 lines and further provided with parallel cuts disposed at right angles to the groups of score lines, each cut being flanked on each side by a score line, said surface sheet being bent on said parallel score lines and said surface sheet being further bent on said score lines, flanking said cuts to provide a plurality of cushioned supports arranged in parallel rows disposed at right angles to each other, with the upper platform forming surface in the same plane and spaced above the surface of the flat, said platforms each being provided with a recess and the bent portions thereof flanking said cuts resting on the upper surface of the separating flat. 35 40

In testimony whereof I have signed my name to this specification.

ROBERT W. BURROWS.
